UNITED STATES PATENT OFFICE

149,336

DESIGN FOR A GAME BOARD

Sam Binder, Los Angeles, Calif., assignor to World Games, Inc., Los Angeles County, Calif., a corporation of California

Application August 19, 1946, Serial No. 132,633

Term of patent 3½ years

(Cl. D34—5)

To all whom it may concern:

Be it known that I, Sam Binder, a citizen of the United States, residing at Los Angeles, in the county of Los Angeles and State of California, have invented a new, original, and ornamental Design for a Game Board, of which the following is a specification, reference being had to the accompanying drawing, forming part thereof.

The figure is a plan view of a game board, showing my new design.

The thickness of the game board is conventional.

I claim:

The ornamental design for a game board, as shown, and described.

SAM BINDER.
